Fig. 4

Fig. 6

FIG. 1 is a top plan view of a disposable diaper showing my new design;

FIG. 2 is a bottom view of the disposable diaper shown in FIG. 1;

FIG. 3 is an enlarged portion of the design as indicated by 3 in FIG. 1;

FIG. 4 is an enlarged portion of the design as indicated by 4 in FIG. 1;

FIG. 5 is a side elevation view taken in the direction of 5-5 of FIG. 1;

FIG. 6 is a transverse sectional view taken along line 6-6 of FIG. 1.

I claim:

The ornamental design for disposable diapers, as shown and described.
